UNITED STATES PATENT OFFICE.

WILLIAM H. ADAMS, OF KENYON, RHODE ISLAND, ASSIGNOR TO EASTERN FINISHING WORKS, INCORPORATED, OF KENYON, RHODE ISLAND, A CORPORATION OF RHODE ISLAND.

DESIGN FOR TEXTILE FABRIC OR ARTICLE OF SIMILAR NATURE.

Application filed September 15, 1923. Serial No. 7,215. Term of patent 14 years.

To all whom it may concern:

Be it known that I, WILLIAM H. ADAMS, a citizen of the United States, residing at Kenyon, in the county of Washington and State of Rhode Island, have invented a new, original, and ornamental Design for Textile Fabric or Article of Similar Nature, of which the following is a specification, reference being had to the accompanying drawing, forming part thereof.

The drawing is a face view of a piece of fabric, illustrating the design.

I claim:

The ornamental design for textile fabric or article of similar nature substantially as shown.

WM. H. ADAMS.
